To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of my design consists of a series of ornamental scrolls connected in the form of a heart-shaped panel, with a small circle or kite-shaped ornament arranged at the top and formed by ornamental scrolls, 15 with festoons of flowers and leaves hanging from various points of said ornaments, as rep-

resented in the accompanying drawing. A vase of flowers is arranged on each side of the scrolls forming the ornamental panels and form part of said design. 20

The design is printed in any desired color upon tinted paper of any desired color.

What I claim is—
